CLAIM

The ornamental design for electrode assembly, as shown and described.

DESCRIPTION

FIG. 1 is a top, front perspective view of an electrode assembly showing our new design,

FIG. 2 is a top plan view thereof;

FIG. 3 is a bottom plan view thereof;

FIG. 4 is a left side elevation view thereof;

FIG. 5 is a right side elevation view thereof;

FIG. 6 is a front view elevation thereof; and,

FIG. 7 is a rear view elevation thereof.

The broken lines in the drawings depict environmental structure and form no part of the claimed design.
